UNITED STATES PATENT OFFICE

KARL POHLHAUSEN, OF BERLIN-HALENSEE, GERMANY, ASSIGNOR TO SIEMENS-SCHUCKERTWERKE AKTIENGESELLSCHAFT, OF BERLIN-SIEMENSSTADT, GERMANY, A CORPORATION OF GERMANY

ELECTRON TUBE

Application filed May 15, 1929, Serial No. 363,157, and in Germany May 12, 1928.

My invention relates to improvements in electron tubes, and more particularly in high-power electron or thermionic cathode tubes as used in the transmitting stations of radio communication plants.

One object of my invention is to protect the filament shaped thermionic cathode of the electron tube against mechanical stresses originating from electrostatic forces exerted upon said cathode.

A further object of my invention consists in providing the electron tube with auxiliary electrodes the potential of which lies in the vicinity of the cathode potential (preferably agrees with the cathode potential) and which are so located, that the electrostatic forces exerted on the cathode are reduced to a minimum.

A still further object of my invention is to provide a thermionic cathode tube with an anode cylinder within which the filament-like elements of the cathode, which are substantially parallel to the axis of the anode cylinder, are located on an imaginary cylindrical surface concentric to the anode cylinder, rod-shaped auxiliary electrodes parallel to the axis of the anode cylinder being provided, which are likewise located on an imaginary cylindrical surface enclosing the cylinder on which are located the filament elements.

These and other embodiments of my invention will be more fully described with reference to the accompanying drawing hereto. In which

35 Figs. 1 and 2 represent transverse sections through the electrode structure of a thermionic tube, according to my invention, showing two forms in which the invention may be reduced to practice,

40 Fig. 3 is a diagrammatic representation of the arrangement of the electric connections between the several filament lengths, and

45 Fig. 4 represents the general arrangement of such an electrode structure, involving either of the foregoing modifications, in a thermionic tube.

Referring to Figs. 1 and 2, 1 is the cylindrical anode, in this case of hollow cylindrical form, which may be arranged in an evacuated vessel 6 for instance as shown in Fig. 4.

The thermionic cathode structure is disposed within this anode cylinder. The cathode itself consists of a plurality of filament lengths arranged physically substantially in parallel to one another. Electrically these lengths 55 may be connected together in any approved manner, such as in series, for instance as shown in Fig. 3. These filament lengths are located between a number of rod shaped parallel auxiliary electrodes electrically connected to the filament cathode, so that they have substantially the same average potential as the filament with respect to the anode. They thus screen the several filament lengths 60 against the electrostatic forces emanating 65 from the anode. They may serve at the same time as supports for the filaments.

In the modification illustrated in Fig. 1 four rod-shaped auxiliary electrodes 3, having the same potential as the filaments, are 70 located at the corners of a square, while the four filaments 2 are arranged within this square symmetrically to the holders.

In the modification illustrated in Fig. 2 the individual filaments and rod-shaped auxiliary electrodes are arranged in concentric 75 circles, the auxiliary electrodes being placed on the outer circle, two rods being always located in the vicinity of each filament length and symmetrically to it. The auxiliary electrodes again would possess substantially the potential of the heated filaments 80 2.

From Fig. 2 it will be noted that the screening against the anode is much more effective than in Fig. 1. The arrows emanating in 85 that figure from one of the filament lengths indicate the planes in which each filament length is screened by several auxiliary electrodes which are located in each of the planes. Each filament length is thus arranged at the 90 intersection of the shielding planes.

If the auxiliary electrodes serve in such arrangements at the same time as holders for the cathode one or more of these auxiliary electrodes may also be used as leading-in and 95 leading-out wires for the heating current of the cathode as shown in Figs. 3 and 4. The remaining auxiliary electrodes have then only screening function. In both cases it is possible to arrange the leading-in or the lead- 100

ing-out wire of the heating current on the same side of the electron tube.

In the following is given a formula indicating how the individual filaments and rod-shaped auxiliary electrodes should be arranged and dimensioned, if we consider in Fig. 3 the two outer filaments located in one plane between two auxiliary electrodes. In this example

10 R represents the radius of the anode cylinder,

r_1 is the radius of the filaments,

15 r_0 the radius of the rod-shaped auxiliary electrodes,

d_1 the distance of the auxiliary electrodes from the axis of the anode cylinder, and

15 d_2 the distance of the filaments from the axis of the anode cylinder.

20 If now $\frac{r_0}{R}$ is chosen = 0.05, and $\frac{r_1}{R}$ = 0.01,

an accurate calculation for $\frac{d_1}{R}$ = 0.7 gives as

25 place for the filament free from electro-

static forces $\frac{d_2}{R}$ = 0.225. For $\frac{d_1}{R}$ = 0.5 results

30 $\frac{d_2}{R}$ = 0.145.

35 The arrangements described have incidentally the advantage, that mutual the electrodynamic forces exerted by the heating current on the heated lengths are to a large extent equalized, if in accordance with Fig. 3 of the drawing the heated filaments are consecutively connected in series, so that the field forces in the individual current loops very nearly compensate one another.

40 Various modifications and changes may be made without departing from the spirit and the scope of the invention.

I claim as my invention:

45 1. An electron tube having an anode and a thermionic cathode mounted within said anode, said cathode consisting of a plurality of substantially parallel filaments, and a plurality of mechanically resistive auxiliary electrodes mounted in parallel to said filaments and at the corners of a polygon which includes said filaments, some of the polygon sides including each at least one of the said filaments, whereby each of said filaments included in a polygon side is shielded by two of said electrodes in a direction co-planar with the polygon side against the electrostatic forces exerted by the anode.

50 2. An electron tube having an anode and a thermionic cathode mounted within said anode, said cathode consisting of a plurality of substantially parallel filaments, and a plurality of mechanically resistive auxiliary electrodes mounted in parallel to said filaments and at the corners of a regular polygon, said filaments being disposed on at

least two opposite sides of said polygon, whereby each of said filaments included in a polygon side is shielded by two of said electrodes in a direction co-planar with the polygon side against the electrostatic forces exerted by the anode.

55 3. An electron tube having an anode and a thermionic cathode mounted within said anode, said cathode consisting of a plurality of substantially parallel filaments, and a plurality of mechanically resistive auxiliary electrodes mounted in parallel to said filaments and at the corners of a regular polygon, said filaments being disposed on a circle inscribed within the contour of said polygon, each filament being disposed in a plane through two auxiliary electrodes of said polygon, whereby each of said filaments included in such a plane is shielded in the direction of said plane by two auxiliary electrodes within said plane against the electrostatic forces exerted by the anode.

60 4. An electron tube having an anode and a thermionic cathode mounted within said anode, said cathode consisting of a plurality of substantially parallel filaments, and a plurality of mechanically resistive auxiliary electrodes mounted in parallel to said filaments and at the corners of a regular polygon, said filaments being disposed on a circle inscribed within the contour of said polygon, each filament being disposed at the intersection of two planes through two pairs of auxiliary electrodes, whereby each filament is shielded in the directions of its pertaining planes by the pertaining electrodes against the electrostatic forces exerted by said anode.

65 In testimony whereof I affix my signature.
KARL POHLHAUSEN.
